ANTENNA APPARATUS

CROSS-REFERENCE TO RELATED
APPLICATION(S)

This application claims the benefit under 35 USC § 119(a) of Korean Patent Application No. 10-2019-0149283 filed on Nov. 20, 2019 in the Korean Intellectual Property Office, the entire disclosure of which is incorporated herein by reference for all purposes.

BACKGROUND

1. Field

The following description relates to an antenna apparatus.

2. Description of Background

Mobile communications data traffic has increased on an annual basis. Various techniques have been actively developed to support rapidly increasing data in wireless networks in real time. For example, conversion of Internet of Things (IoT)-based data into contents, augmented reality (AR), virtual reality (VR), live VR/AR linked with SNS, an automatic driving function, applications such as a sync view (transmission of real-time images from a user's viewpoint using a compact camera), and the like, may require communications (e.g., 5G communications, mmWave communications, and the like) which support the transmission and reception of large volumes of data.

Accordingly, there has been a large amount of research on mmWave communications including 5th generation (5G), and the research into the commercialization and standardization of an antenna apparatus for implementing such communications has been increasingly conducted.

A radio frequency (RF) signal of a high frequency band (e.g., 24 GHz, 28 GHz, 36 GHz, 39 GHz, 60 GHz, and the like) may easily be absorbed and lost while being transmitted, which may degrade quality of communications. Thus, an antenna for communications performed in a high frequency band may require a technical approach different from techniques used in a general antenna, and a special technique such as a separate power amplifier, and the like, may be required to secure antenna gain, integration of an antenna and an RFIC, effective isotropic radiated power (EIRP), and the like.

SUMMARY

This Summary is provided to introduce a selection of concepts in simplified form that are further described below in the Detailed Description. This Summary is not intended to identify key features or essential features of the claimed subject matter, nor is it intended to be used as an aid in determining the scope of the claimed subject matter.

An antenna apparatus which may improve antenna performance (e.g., gain, bandwidth, directivity, etc.), and/or may be easily miniaturized.

In one general aspect, an antenna apparatus includes a ground plane; a first patch antenna pattern disposed above and spaced apart from a first surface of the ground plane; a second patch antenna pattern disposed above and spaced apart from the first surface of the ground plane, and spaced apart from the first patch antenna pattern; a first feed via configured to provide a first feed path of the first patch antenna pattern through a first point of the first patch antenna

2

pattern, and disposed adjacent to an edge of the first patch antenna pattern in a direction in which the first point is spaced apart from the second patch antenna pattern; a second feed via configured to provide a second feed path of the second patch antenna pattern through a second point of the second patch antenna pattern, and disposed adjacent to an edge of the second patch antenna pattern in a direction in which the second point is spaced apart from the first patch antenna pattern; and a first coupling pattern disposed between the first patch antenna pattern and the second patch antenna pattern, and spaced apart from the first patch antenna pattern and the second patch antenna pattern, and configured to define a first internal space of the first coupling pattern that is exposed towards the first patch antenna pattern.

The antenna apparatus may include a second coupling pattern disposed between the second patch antenna pattern and the first coupling pattern, and spaced apart from the first coupling pattern, and configured to define a second internal space of the second coupling pattern that is exposed towards the second patch antenna pattern.

The antenna apparatus may include a first ground via electrically connecting the first coupling pattern to the ground plane; and a second ground via electrically connecting the second coupling pattern to the ground plane.

The first ground via may be electrically connected to a point of the first coupling pattern adjacent to the second coupling pattern, and the second ground via may be electrically connected to a point of the second coupling pattern adjacent to the first coupling pattern.

A gap between the first coupling pattern and the second coupling pattern may be smaller than a gap between the first coupling pattern and the first patch antenna pattern.

A length of the first coupling pattern along a direction perpendicular to a direction in which the first and second coupling patterns oppose each other may be larger than a width of the first coupling pattern.

The antenna apparatus may include an upper coupling pattern disposed above and spaced apart from the first coupling pattern and the second coupling pattern such that the first coupling pattern and the second coupling pattern are disposed between the ground plane and the upper coupling pattern along a direction perpendicular to the first surface of the ground plane, and configured to overlap the first coupling pattern and the second coupling pattern in the direction perpendicular to the first surface of the ground plane.

The upper coupling pattern may be configured to overlap a gap between the first coupling pattern and the second coupling pattern, the first internal space of the first coupling pattern, and the second internal space of the second coupling pattern in a direction perpendicular to the first surface of the ground plane.

The antenna apparatus may include a first upper patch pattern disposed above and spaced apart from the first patch antenna pattern; a second upper patch pattern disposed above and spaced apart from the second patch antenna pattern; and a supplementary patch pattern spaced apart from the upper coupling pattern along a direction different from at least one direction in which the supplementary patch pattern spaced is apart from the first upper patch pattern and the second upper patch pattern.

The supplementary patch pattern may include a plurality of supplementary patch patterns spaced apart from each other, and each having a size smaller than a size of the upper coupling pattern.

The antenna apparatus may include a first upper patch pattern disposed above and spaced apart from the first patch

antenna pattern; a second upper patch pattern disposed above and spaced apart from the second patch antenna pattern; and an upper coupling pattern disposed above and spaced apart from the first coupling pattern, and configured to overlap the first coupling pattern in a direction perpendicular to the first surface of the ground plane.

The antenna apparatus may include a third patch antenna pattern disposed above and spaced apart from the first surface of the ground plane, and spaced apart from the first patch antenna pattern and the second patch antenna pattern; a fourth patch antenna pattern disposed above and spaced apart from the first surface of the ground plane and spaced apart from the first patch antenna pattern, the second patch antenna pattern, and the third patch antenna pattern; a third coupling pattern disposed between the first patch antenna pattern and the third patch antenna pattern, and spaced apart from the first patch antenna pattern and the third patch antenna pattern, and configured to define a third internal space of the third coupling pattern that is exposed towards the first patch antenna pattern; and a fourth coupling pattern disposed between the second patch antenna pattern and the fourth patch antenna pattern, and spaced apart from the second patch antenna pattern and the fourth patch antenna pattern, and configured to define a fourth internal of the fourth coupling pattern space that is exposed towards the second patch antenna pattern.

The antenna apparatus may include a fifth coupling pattern disposed between the third patch antenna pattern and the fourth patch antenna pattern, and configured to define a fifth internal space of the fifth coupling pattern that is exposed towards the third patch antenna pattern; a sixth coupling pattern spaced disposed between the third patch antenna pattern and the third coupling pattern, and spaced apart from the third coupling pattern, and configured to define a sixth internal space of the sixth coupling pattern that is exposed towards the third patch antenna pattern; a seventh coupling pattern disposed between the fourth patch antenna pattern and the fourth coupling pattern, and spaced apart from the fourth coupling pattern, and configured to define a seventh internal space of the seventh coupling pattern that is exposed towards the fourth patch antenna pattern; and an eighth coupling pattern disposed between the fourth patch antenna pattern and the fifth coupling pattern, and spaced apart from the fifth coupling pattern, and configured to define an eighth internal space of the eighth coupling pattern that is exposed towards the fourth patch antenna pattern.

The antenna apparatus may include a third feed via configured to provide a third feed path of the first patch antenna pattern through a third point of the first patch antenna pattern, and disposed adjacent to an edge of the first patch antenna pattern in a direction in which the third point is spaced apart from the third patch antenna pattern; a fourth feed via configured to provide a fourth feed path of the second patch antenna pattern through a fourth point of the second patch antenna pattern, and disposed adjacent to an edge of the second patch antenna pattern in a direction in which the fourth point is spaced apart from the fourth patch antenna pattern; a fifth feed via configured to provide a fifth feed path of the third patch antenna pattern through a fifth point of the third patch antenna pattern, and disposed adjacent to an edge of the third patch antenna pattern in a direction in which the fifth point is spaced apart from the fourth patch antenna pattern; a sixth feed via configured to provide a sixth feed path of the third patch antenna pattern through a sixth point of the third patch antenna pattern, and disposed adjacent to an edge of the third patch antenna pattern in a direction in which the sixth point is spaced apart

from the first patch antenna pattern; a seventh feed via configured to provide a seventh feed path of the fourth patch antenna pattern through a seventh point of the fourth patch antenna pattern, and disposed adjacent to an edge of the fourth patch antenna pattern in a direction in which the seventh point is spaced apart from the second patch antenna pattern; and an eighth feed via configured to provide an eighth feed path of the fourth patch antenna pattern through an eighth point of the fourth patch antenna pattern, and disposed adjacent to an edge of the fourth patch antenna pattern in a direction in which the eighth point is spaced apart from the third patch antenna pattern.

The antenna apparatus may include a fifth coupling pattern disposed between the third patch antenna pattern and fourth patch antenna patterns, and configured to define a fifth internal space exposed towards the third patch antenna pattern; and a plurality of upper coupling patterns disposed above and spaced apart from the first coupling pattern, the second coupling pattern, the third coupling pattern, the fourth coupling pattern, and the fifth coupling pattern such that the first coupling pattern, the second coupling pattern, the third coupling pattern, the fourth coupling pattern, and the fifth coupling pattern are disposed between the ground plane and the upper coupling patterns along a direction perpendicular to the first surface of the ground plane, and configured to overlap the first coupling pattern, the second coupling pattern, the third coupling pattern, the fourth coupling pattern, and the fifth coupling pattern in the direction perpendicular to the first surface of the ground plane.

The antenna apparatus may include a plurality of supplementary patch patterns surrounded by the upper coupling patterns, spaced apart from each other, and each having a size smaller than a size of each of the upper coupling patterns.

The antenna apparatus may include a supplementary patch pattern surrounded by the upper coupling patterns, and a space overlapping the supplementary patch pattern in the direction perpendicular to the first surface of the ground plane and disposed on a same level as the first coupling pattern, the second coupling pattern, the third coupling pattern, the fourth coupling pattern, and the fifth coupling pattern may be formed of a non-conductive material or air.

Other features and aspects will be apparent from the following detailed description, the drawings, and the claims.

BRIEF DESCRIPTION OF THE DRAWINGS

FIG. 1A is a side view of an antenna apparatus according to an example.

FIGS. 1B, 1C, 1D, and 1E are plan views of an antenna device taken along z direction in order in a-z direction according to an example.

FIGS. 2A, 2B, and 2C are plan views of modified structures of a first conductive layer of an antenna apparatus according to an example.

FIGS. 3A and 3B are plan views of a modified structure of an antenna apparatus according to an example.

FIG. 4A is a plan view of a modified structure of a ground plane of an antenna apparatus according to an example.

FIGS. 4B, 4C, 4D, and 4E are plan views of a structure disposed lower than a ground plane of an antenna apparatus.

FIGS. 4F is a side view of a structure disposed lower than a ground plane of an antenna apparatus.

FIGS. 5A and 5B are side views of a connection member on which a ground plane is stacked, included in an antenna device, and a lower structure of the connection member according to an example.

FIGS. 6A and 6B are plan views of an arrangement of an antenna apparatus in an electronic device according to an example.

Throughout the drawings and the detailed description, the same reference numerals refer to the same elements. The drawings may not be to scale, and the relative size, proportions, and depiction of elements in the drawings may be exaggerated for clarity, illustration, and convenience.

DETAILED DESCRIPTION

The following detailed description is provided to assist the reader in gaining a comprehensive understanding of the methods, apparatuses, and/or systems described herein. However, various changes, modifications, and equivalents of the methods, apparatuses, and/or systems described herein will be apparent to one of ordinary skill in the art. The sequences of operations described herein are merely examples, and are not limited to those set forth herein, but may be changed as will be apparent to one of ordinary skill in the art, with the exception of operations necessarily occurring in a certain order. Also, descriptions of functions and constructions that would be well known to one of ordinary skill in the art may be omitted for increased clarity and conciseness.

The features described herein may be embodied in different forms, and are not to be construed as being limited to the examples described herein. Rather, the examples described herein have been provided so that this disclosure will be thorough and complete, and will fully convey the scope of the disclosure to one of ordinary skill in the art.

Herein, it is noted that use of the term "may" with respect to an example or embodiment, e.g., as to what an example or embodiment may include or implement, means that at least one example or embodiment exists in which such a feature is included or implemented while all examples and embodiments are not limited thereto.

Throughout the specification, when an element, such as a layer, region, or substrate, is described as being "on," "connected to," or "coupled to" another element, it may be directly "on," "connected to," or "coupled to" the other element, or there may be one or more other elements intervening therebetween. In contrast, when an element is described as being "directly on," "directly connected to," or "directly coupled to" another element, there can be no other elements intervening therebetween.

As used herein, the term "and/or" includes any one and any combination of any two or more of the associated listed items.

Although terms such as "first," "second," and "third" may be used herein to describe various members, components, regions, layers, or sections, these members, components, regions, layers, or sections are not to be limited by these terms. Rather, these terms are only used to distinguish one member, component, region, layer, or section from another member, component, region, layer, or section. Thus, a first member, component, region, layer, or section referred to in examples described herein may also be referred to as a second member, component, region, layer, or section without departing from the teachings of the examples.

Spatially relative terms such as "above," "upper," "below," and "lower" may be used herein for ease of description to describe one element's relationship to another element as shown in the figures. Such spatially relative terms are intended to encompass different orientations of the device in use or operation in addition to the orientation depicted in the figures. For example, if the device in the

figures is turned over, an element described as being "above" or "upper" relative to another element will then be "below" or "lower" relative to the other element. Thus, the term "above" encompasses both the above and below orientations depending on the spatial orientation of the device. The device may also be oriented in other ways (for example, rotated 90 degrees or at other orientations), and the spatially relative terms used herein are to be interpreted accordingly.

The terminology used herein is for describing various examples only, and is not to be used to limit the disclosure. The articles "a," "an," and "the" are intended to include the plural forms as well, unless the context clearly indicates otherwise. The terms "comprises," "includes," and "has" specify the presence of stated features, numbers, operations, members, elements, and/or combinations thereof, but do not preclude the presence or addition of one or more other features, numbers, operations, members, elements, and/or combinations thereof.

Due to manufacturing techniques and/or tolerances, variations of the shapes shown in the drawings may occur. Thus, the examples described herein are not limited to the specific shapes shown in the drawings, but include changes in shape that occur during manufacturing.

The features of the examples described herein may be combined in various ways as will be apparent after an understanding of the disclosure of this application. Further, although the examples described herein have a variety of configurations, other configurations are possible as will be apparent after an understanding of the disclosure of this application.

Hereinafter, examples will be described as follows with reference to the attached drawings.

FIG. 1A is a cross-sectional diagram illustrating an antenna apparatus according to an example. FIGS. 1B through 1E are plan diagrams illustrating an antenna device taken along z direction in order in a-z direction according to an example.

An antenna apparatus 100a may have a stack structure in which a plurality of conductive layers and a plurality of dielectric layers are alternately disposed. At least some of the plurality of dielectric layers may be replaced with air. The stack structure may be implemented as a printed circuit substrate (PCB), but embodiment configuration thereof is not limited thereto.

Referring to FIGS. 1A through 1E, the antenna apparatus 100a may include a first conductive layer 101a, a second conductive layer 102a, a third conductive layer 103a, and a fourth conductive layer 104a. A spacing distance between the conductive layers may be appropriately controlled.

For example, the first, second, third, and fourth conductive layers 101a, 102a, 103a, and 104a may be disposed in at least portions of upper surfaces or lower surfaces of the corresponding dielectric layers, respectively, to include a pre-designed conductive pattern or a pre-designed conductive plane, and may be connected to each other in upward and/or downward directions (e.g., +/-z directions) through a conductive via. A width of the conductive via may be appropriately adjusted.

Referring to FIGS. 1A through 1E, the antenna apparatus 100a may include a ground plane 201a, a first patch antenna pattern 110a-1, a second patch antenna pattern 110a-2, a first feed via 120a-8, a second feed via 120a-5, and a first coupling pattern 131a-1.

The ground plane 201a may be disposed on the third conductive layer 103a, and may work as a reference of

impedance corresponding to a resonant frequency of each of the first and second patch antenna patterns **110a-1** and **110a-2**.

The ground plane **201a** may reflect a radio frequency (RF) signal radiated from the first and second patch antenna patterns **110a-1** and **110a-2**, and accordingly, a direction in which radiation patterns of the first and second patch antenna patterns **110a-1** and **110a-2** are formed may be concentrated in a z direction, and gains of the first and second patch antenna patterns **110a-1** and **110a-2** may be improved.

For example, the ground plane **201a** may include at least one through-hole which the first and second feed vias **120a-8** and **120a-5** penetrate, respectively. Accordingly, an electrical length of a feed path provided to the first and second patch antenna patterns **110a-1** and **110a-2** may be easily reduced.

The first and second patch antenna patterns **110a-1** and **110a-2** may be disposed above and spaced apart from an upper surface of the ground plane **201a**, and may be spaced apart from each other. The first and second patch antenna patterns **110a-1** and **110a-2** may be disposed on the second conductive layer **102a**, but the configuration thereof is not limited thereto. For example, at least one of the first and second patch antenna patterns **110a-1** and **110a-2** may be disposed on a level higher or lower than the second conductive layer **102a**.

Each of the first and second patch antenna patterns **110a-1** and **110a-2** may have a bandwidth based on an intrinsic resonant frequency determined in accordance with an intrinsic element (e.g., a shape, a size, a thickness, a spacing distance, a dielectric constant of a dielectric layer, or others) and an extrinsic resonant frequency determined in accordance with an electromagnetic coupling with an adjacent conductive structure.

When a frequency of an RF signal is included in the bandwidth described above, the first and second patch antenna patterns **110a-1** and **110a-2** may receive an RF signal from the first and second feed vias **120a-8** and **120a-5**, and may remotely transmit the RF signal in the z direction, or may transfer a remotely received RF signal to the first and second feed vias **120a-8** and **120a-5**. The first and second feed vias **120a-8** and **120a-5** may provide an electrical connection path between an integrated circuit (IC) and the first and second patch antenna patterns **110a-1** and **110a-2**, and may work as a transmission line of an RF signal.

The first feed via **120a-8** may be configured to provide a first feed path of the first patch antenna pattern **110a-1** through a point of the first patch antenna pattern **110a-1** disposed adjacent to an edge of the first patch antenna pattern **110a-1** in a direction (e.g., -x direction) in which the point is spaced apart from the second patch antenna pattern **110a-2**.

The second feed via **120a-5** may be configured to provide a second feed path of the second patch antenna pattern **110a-2** through a point of the second patch antenna pattern **110a-2** disposed adjacent to an edge of the second patch antenna pattern **110a-2** in a direction (e.g., +x direction) in which the point is spaced apart from the first patch antenna pattern **110a-1**.

The direction in which the first feed via **120a-8** is disposed adjacent to the edge of the first patch antenna pattern **110a-1** may be opposite to the direction in which the second feed via **120a-5** is disposed adjacent to the edge of the second patch antenna pattern **110a-2**.

Accordingly, the first and second feed paths may be disposed adjacent to an edge of the antenna apparatus **100a**,

an electrical length from the first and second patch antenna patterns **110a-1** and **110a-2** to an IC may be reduced, and transmission loss of first and second RF signals transmitted to and received from the first and second patch antenna patterns **110a-1** and **110a-2** may be reduced.

As the direction in which the first feed via **120a-8** is adjacent to the edge of the first patch antenna pattern **110a-1** is opposite to the direction in which the second feed via **120a-5** is adjacent to the edge of the second patch antenna pattern **110a-2**, the first and second feed paths from the first and second patch antenna patterns **110a-1** and **110a-2** to the IC may be simplified. Accordingly, an overall size of the antenna apparatus **100a** may be reduced.

Upper surfaces of the first and second patch antenna patterns **110a-1** and **110a-2** may work as a space in which a surface current flows, and electromagnetic energy corresponding to the surface current may be radiated towards the air in normal directions of upper surfaces of the first and second patch antenna patterns **110a-1** and **110a-2** in accordance with resonance of the first and second patch antenna patterns **110a-1** and **110a-2**, respectively. The position in which the first and second feed vias **120a-8** and **120a-5** provide the first and second feed paths may work as a reference point of the surface current.

As the direction in which the first feed via **120a-8** is adjacent to the edge of the first patch antenna pattern **110a-1** is opposite to the direction in which the second feed via **120a-5** is adjacent to the edge of the second patch antenna pattern **110a-2**, the direction in which a first surface current of the first patch antenna pattern **110a-1** flows may be opposite to the direction in which a second surface current of the second patch antenna pattern **110a-2** flows.

The directions in which the first and second surface currents flow may correspond to a direction of an electrical field and a direction of a magnetic field, formed when the first and second patch antenna patterns **110a-1** and **110a-2** remotely transmit and receive an RF signal. As the direction in which the first surface current flows is opposite to the direction in which the second current surface flows, the directions of first and second electrical fields corresponding to the first and second surface currents may be opposite to each other, and the directions of first and second magnetic fields corresponding to the first and second surface currents may be opposite to each other.

Accordingly, overlapping efficiency of the first and second radiation patterns of the first and second patch antenna patterns **110a-1** and **110a-2** may be an antenna design element.

The first coupling pattern **131a-1** may be spaced apart from the first and second patch antenna patterns **110a-1** and **110a-2** between the first and second patch antenna patterns **110a-1** and **110a-2**, and may be configured to surround a first internal space to expose the first internal space towards the first patch antenna pattern **110a-1**. A width **W4** and an exposed width **W3** of the first internal space may be appropriately adjusted. Likewise, a dimension **W2** of the first coupling pattern **131a-1** in the x-direction may be appropriately adjusted.

The first coupling pattern **131a-1** may be electromagnetically coupled to the first patch antenna pattern **110a-1**, and may thus provide impedance to the first patch antenna pattern **110a-1**. As the impedance may affect a resonant frequency of the first patch antenna pattern **110a-1**, the first patch antenna pattern **110a-1** may increase a gain or may broaden a bandwidth in accordance with the electromagnetic coupling with the first coupling pattern **131a-1**.

As the first coupling pattern **131a-1** is disposed between the first and second patch antenna patterns **110a-1** and **110a-2**, a first surface current flowing in the first patch antenna pattern **110a-1** may electromagnetically flow to the first coupling pattern **131a-1** through the coupling. Accordingly, the first coupling pattern **131a-1** may additionally provide an area in which the first surface current flows.

As the first coupling pattern **131a-1** surrounds a first internal space to expose the first internal space of the first coupling pattern **131a-1** towards the first patch antenna pattern **110a-1**, the first surface current flowing from the first patch antenna pattern **110a-1** to the first coupling pattern **131a-1** may flow in a direction of returning to the first patch antenna pattern **110a-1**.

Accordingly, a portion of the first radiation pattern of the first patch antenna pattern **110a-1** relatively close to the second patch antenna pattern **110a-2** may have electromagnetically harmonious properties with respect to the second radiation pattern of the second patch antenna pattern **110a-2**.

Accordingly, the first and second radiation patterns of the first and second patch antenna patterns **110a-1** and **110a-2** may overlap each other electromagnetically in an efficient manner such that an overall gain of the antenna apparatus **100a** may efficiently improve. The higher the number of the first and second patch antenna patterns **110a-1** and **110a-2**, the more the gain may increase, and the antenna apparatus **100a** may improve a gain for a size.

Referring to FIGS. 1A through 1E, the antenna apparatus **100a** may further include a second coupling pattern **132a-1** configured to be spaced apart from the first coupling pattern **131a-1** between the second patch antenna pattern **110a-2** and the first coupling pattern **131a-1** and to surround a second internal space to expose the second internal space towards the second patch antenna pattern **110a-2**.

Accordingly, a second surface current flowing from the second patch antenna pattern **110a-2** to the second coupling pattern **132a-1** may flow in a direction of returning to the second patch antenna pattern **110a-2** such that a portion of the second radiation pattern of the second patch antenna pattern **110a-2** relatively adjacent to the first patch antenna pattern **110a-1** may have electromagnetically harmonious properties with respect to the first radiation pattern of the first patch antenna pattern **110a-1**.

Referring to FIGS. 1A through 1E, the antenna apparatus **100a** may further include a first ground via **123a-1** and/or a second ground via **124a-1**.

The first ground via **123a-1** may electrically connect the first coupling pattern **131a-1** to the ground plane **201a**, and the second ground via **124a-1** may electrically connect the second coupling pattern **132a-1** to the ground plane **201a**.

Accordingly, the first ground via **123a-1** may work as an inductance element of a resonant frequency of the first patch antenna pattern **110a-1**, and the second ground via **124a-1** may work as an inductance element of a resonant frequency of the second patch antenna pattern **110a-2**. Accordingly, the first and second patch antenna patterns **110a-1** and **110a-2** may have a relatively broad bandwidth.

The first and second ground vias **123a-1** and **124a-1** may provide electromagnetically stable properties of a ground of the ground plane **201a** to the first and second coupling patterns **131a-1** and **132a-1**. Accordingly, a combined structure of the first and second ground vias **123a-1** and **124a-1** and the first and second coupling patterns **131a-1** and **132a-1** may reduce electromagnetic noise of the first and second patch antenna patterns **110a-1** and **110a-2**, electromagnetic noise of which may affect the first and second patch antenna patterns **110a-1** and **110a-2** mutually.

For example, the first ground via **123a-1** may be electrically connected to a point of the first coupling pattern **131a-1** adjacent to the second coupling pattern **132a-1**, and the second ground via **124a-1** may be electrically connected to a point of the second coupling pattern **132a-1** adjacent to the first coupling pattern **131a-1**.

Accordingly, the first coupling pattern **131a-1** may be more intensively electrically coupled to the first patch antenna pattern **110a-1** than to the second patch antenna pattern **110a-2**, and the second coupling pattern **132a-1** may be more intensively electrically coupled to the second patch antenna pattern **110a-2** than to the first patch antenna pattern **110a-1**. Accordingly, electromagnetic noise of the first and second patch antenna patterns **110a-1** and **110a-2**, electromagnetic noise of which may affect the first and second patch antenna patterns **110a-1** and **110a-2** mutually, may be reduced, and the first and second radiation patterns of the first and second patch antenna patterns **110a-1** and **110a-2** may electromagnetically overlap with each other in an efficient manner.

For example, a gap 'g' between the first and second coupling patterns **131a-1** and **132a-1** may be smaller than a gap **d1** between the first coupling pattern **131a-1** and the first patch antenna pattern **110a-1**, and a length **W1** of the first coupling pattern **131a-1** and/or the second coupling pattern **132a-1** taken in a direction perpendicular to a direction in which the first and second coupling patterns **131a-1** and **132a-1** oppose each other may be longer than a width **W5**.

Accordingly, a combined structure of the first and second coupling patterns **131a-1** and **132a-1** may effectively work as a capacitance element of a resonant frequency of each of the first and second patch antenna patterns **110a-1** and **110a-2**, such that the first and second patch antenna patterns **110a-1** and **110a-2** may have a broad bandwidth.

Referring to FIGS. 1A through 1E, at least some of upper coupling patterns **137a-1**, **137a-2**, **137a-3**, and **137a-4** included in the antenna apparatus **100a** may be disposed on the first conductive layer **101a**.

At least some of the upper coupling patterns **137a-1**, **137a-2**, **137a-3**, and **137a-4** may be disposed above and spaced apart from upper surfaces of the first and second coupling patterns **131a-1** and **132a-1**, and may overlap the first and second coupling patterns **131a-1** and **132a-1** in upward and/or downward directions (e.g., $+/-z$ directions).

Accordingly, a combined structure of the upper coupling patterns **137a-1**, **137a-2**, **137a-3**, and **137a-4** and the first and second coupling patterns **131a-1** and **132a-1** may work as a capacitance element of a resonant frequency of each of the first and second patch antenna patterns **110a-1** and **110a-2** such that the first and second patch antenna patterns **110a-1** and **110a-2** may have a broad bandwidth.

For example, at least some of the upper coupling patterns **137a-1**, **137a-2**, **137a-3**, and **137a-4** may have a polygonal shape (e.g., a rectangular shape) to overlap a space between the first and second coupling patterns **131a-1** and **132a-1**, the first internal space of the first coupling pattern **131a-1**, and the second internal space of the second coupling pattern **132a-1** in upward and/or downward directions.

A length **IP1** and/or a width **WP1** of at least some of the upper coupling patterns **137a-1**, **137a-2**, **137a-3**, and **137a-4** may be adjusted to correspond to a wavelength corresponding to resonant frequencies of the first and second patch antenna patterns **110a-1** and **110a-2**. The first and second patch antenna patterns **110a-1** and **110a-2** may have a broad bandwidth using the length **IP1** and/or the width **WP1** of at least some of the upper coupling patterns **137a-1**, **137a-2**, **137a-3**, and **137a-4**.

Referring to FIGS. 1A through 1E, a first upper patch pattern **115a-1**, a second upper patch pattern **115a-2**, and at least one of supplementary patch patterns **136a-1**, **136a-2**, **136a-3**, and **136a-4**, included in the antenna apparatus **100a**, may be disposed on the first conductive layer **101a**.

As the first and second patch antenna patterns **110a-1** and **110a-2** are disposed on the second conductive layer **102a**, the first upper patch pattern **115a-1** may be disposed above and spaced apart from an upper surface of the first patch antenna pattern **110a-1**, and the second upper patch pattern **115a-2** may be disposed above and spaced apart from an upper surface of the second patch antenna pattern **110a-2**.

The first and second upper patch patterns **115a-1** and **115a-2** may be electromagnetically coupled to the first and second patch antenna patterns **110a-1** and **110a-2**, and may thus provide additional impedance to the first and second patch antenna patterns **110a-1** and **110a-2**. As the first and second patch antenna patterns **110a-1** and **110a-2** may have additional resonant frequency based on the additional impedance, the first and second patch antenna patterns **110a-1** and **110a-2** may have a broad bandwidth. A length W_{dir} of each of the first and second upper patch patterns **115a-1** and **115a-2** may be appropriately adjusted, and the additional impedance may correspond to the length W_{dir} of each of the first and second upper patch patterns **115a-1** and **115a-2**.

The supplementary patch patterns **136a-1**, **136a-2**, **136a-3**, and **136a-4** may be spaced apart from the upper coupling pattern **137a-1** in a direction (e.g., y direction) different from a direction (e.g., x direction) of the first and second upper patch patterns **115a-1** and **115a-2**.

Accordingly, the supplementary patch patterns **136a-1**, **136a-2**, **136a-3**, and **136a-4** may be electromagnetically coupled to the upper coupling pattern **137a-1**, and may affect a resonant frequency of each of the first and second patch antenna patterns **110a-1** and **110a-2**. Accordingly, the first and second patch antenna patterns **110a-1** and **110a-2** may have a broad bandwidth.

For example, the supplementary patch patterns **136a-1**, **136a-2**, **136a-3**, and **136a-4** may include a plurality of supplementary patch patterns **136a-1**, **136a-2**, **136a-3**, and **136a-4** each having a dimension WP_2 smaller than each of the upper coupling patterns **137a-1**, **137a-2**, **137a-3**, and **137a-4**, and spaced apart from each other by a predetermined gap 'S'.

Accordingly, a bandwidth of each of the first and second patch antenna patterns **110a-1** and **110a-2** may be broadened.

Referring to FIGS. 1A through 1E, at least one of a third upper patch pattern **115a-3** and a fourth upper patch pattern **115a-4** included in the antenna apparatus **100a** may be disposed on the first conductive layer **101a**, and at least one of a third patch antenna pattern **110a-3** and a fourth patch antenna pattern **110a-4** included in the antenna apparatus **100a** may be disposed on the second conductive layer **102a**.

The third patch antenna pattern **110a-3** may be disposed above and spaced apart from the ground plane **201a**, and may be spaced apart from the first and second patch antenna patterns **110a-1** and **110a-2**. The fourth patch antenna pattern **110a-4** may be disposed above and spaced apart from the upper surface of the ground plane **201a**, and may be spaced apart from the first, second, and third patch antenna patterns **110a-1**, **110a-2**, and **110a-3**.

Accordingly, the first, second, third, and fourth patch antenna patterns **110a-1**, **110a-2**, **110a-3**, and **110a-4** may be arranged in a lattice structure, and a total number of the patch antenna patterns for an overall size of each of the patch

antenna patterns may increase in the antenna apparatus **100a**, and the antenna apparatus **100a** in the example may have a relatively high gain for an overall size.

Referring to FIGS. 1A through 1E, the antenna apparatus **100a** may further include first, second, third, fourth, fifth, sixth, seventh, and eighth feed vias **120a-8**, **120a-5**, **120a-2**, **120a-1**, **120a-7**, **120a-3**, **120a-4**, and **120a-6**.

The third feed via **120a-2** may be configured to provide a third feed path of the first patch antenna pattern **110a-1** through a point of the first patch antenna pattern **110a-1** disposed adjacent to an edge of the first patch antenna pattern **110a-1** in a direction (e.g., -y direction) in which the point is spaced apart from the third patch antenna pattern **110a-3**.

The fourth feed via **120a-1** may be configured to provide a fourth feed path of the second patch antenna pattern **110a-2** through a point of the second patch antenna pattern **110a-2** disposed adjacent to an edge of the second patch antenna pattern **110a-2** in a direction (e.g., -y direction) in which the point is spaced apart from the fourth patch antenna pattern **110a-4**.

The fifth feed via **120a-7** may be configured to provide a fifth feed path of the third patch antenna pattern **110a-3** through a point of the third patch antenna pattern **110a-3** disposed adjacent to an edge of the third patch antenna pattern **110a-3** in a direction (e.g., -x direction) in which the point is spaced apart from the fourth patch antenna pattern **110a-4**.

The sixth feed via **120a-3** may be configured to provide a sixth feed path of the third patch antenna pattern **110a-3** through a point of the third patch antenna pattern **110a-3** disposed adjacent to an edge of the third patch antenna pattern **110a-3** in a direction (e.g., +y direction) in which the point is spaced apart from the first patch antenna pattern **110a-1**.

The seventh feed via **120a-4** may be configured to provide a seventh feed path of the fourth patch antenna pattern **110a-4** through a point of the fourth patch antenna pattern **110a-4** disposed adjacent to an edge of the fourth patch antenna pattern **110a-4** in a direction (e.g., +y direction) in which the point is spaced apart from the second patch antenna pattern **110a-2**.

The eighth feed via **120a-6** may be configured to provide an eighth feed path of the fourth patch antenna pattern **110a-4** through a point of the fourth patch antenna pattern **110a-4** disposed adjacent to an edge of the fourth patch antenna pattern **110a-4** in a direction (e.g., +x direction) in which the point is spaced apart from the third patch antenna pattern **110a-3**.

Accordingly, the first, second, third, fourth, fifth, sixth, seventh, and eighth feed vias **120a-8**, **120a-5**, **120a-2**, **120a-1**, **120a-7**, **120a-3**, **120a-4**, and **120a-6** may be disposed adjacent to the edges of the antenna apparatus **100a**, and an electrical length from the first, second, third, and fourth patch antenna patterns **110a-1**, **110a-2**, **110a-3**, and **110a-4** to the IC may be reduced. Also, transmission loss of first, second, third, and fourth RF signals transmitted to and received from the first, second, third, and fourth patch antenna patterns **110a-1**, **110a-2**, **110a-3**, and **110a-4** may decrease. Further, the overall first, second, third, fourth, fifth, sixth, seventh, and eighth feed paths may be simplified. Accordingly, an overall size of the antenna apparatus **100a** may be reduced.

The first, second, third, and fourth patch antenna patterns **110a-1**, **110a-2**, **110a-3**, and **110a-4** may be provided with a plurality of feed paths from the plurality of feed vias, respectively. A surface current of an RF signal flowing

through one of the plurality of feed vias and a surface current of an RF signal flowing through the other one of the plurality of feed vias may be orthogonal to each other, and may implement a polarized wave. As different pieces of communication data may be included in the plurality of RF signals in a mutual polarized relationship, the first, second, third, and fourth patch antenna patterns **110a-1**, **110a-2**, **110a-3**, and **110a-4** may be provided with the plurality of feed paths from the plurality of feed vias, thereby obtaining a relatively high transmission and/or reception rate.

Referring to FIGS. 1A through 1E, at least one of a third coupling pattern **131a-2**, a fourth coupling pattern **131a-3**, a fifth coupling pattern **131a-4**, a sixth coupling pattern **132a-2**, a seventh coupling pattern **132a-3**, and an eighth coupling pattern **132a-4** may be disposed on the second conductive layer **102a**.

The third coupling pattern **131a-2** may be spaced apart from the first and third patch antenna patterns **110a-1** and **110a-3** between the first and third patch antenna patterns **110a-1** and **110a-3**, and may be configured to surround a third internal space to expose the third internal space towards the first patch antenna pattern **110a-1**.

The fourth coupling pattern **131a-3** may be spaced apart from the second and fourth antenna patterns **110a-2** and **110a-4** between the second and fourth antenna patterns **110a-2** and **110a-4**, and may be configured to surround a fourth internal space to expose the fourth internal space towards the second patch antenna pattern **110a-2**.

The fifth coupling pattern **131a-4** may be spaced apart from the third and fourth antenna patterns **110a-3** and **110a-4** between the third and fourth antenna patterns **110a-3** and **110a-4**, and may be configured to surround a fifth internal space to expose the fifth internal space towards the third patch antenna pattern **110a-3**.

The sixth coupling pattern **132a-2** may be spaced apart from the third coupling pattern **131a-2** between the third patch antenna pattern **110a-3** and the third coupling pattern **131a-2**, and may be configured to surround a sixth internal space to expose the sixth internal space towards the third patch antenna pattern **110a-3**.

The seventh coupling pattern **132a-3** may be spaced apart from the fourth coupling pattern **131a-3** between the fourth patch antenna pattern **110a-4** and the fourth coupling pattern **131a-3**, and may be configured to surround a seventh internal space to expose the seventh internal space towards the fourth patch antenna pattern **110a-4**.

The eighth coupling pattern **132a-4** may be spaced apart from the fifth coupling pattern **131a-4** between the fourth patch antenna pattern **110a-4** and the fifth coupling pattern **131a-4**, and may be configured to surround an eighth internal space to expose the eighth internal space towards the fourth patch antenna pattern **110a-4**.

Accordingly, a surface current flowing from the first, second, third, and fourth patch antenna patterns **110a-1**, **110a-2**, **110a-3**, and **110a-4** to the first, second, third, fourth, fifth, sixth, seventh, and eighth coupling patterns **131a-1**, **131a-2**, **131a-3**, **131a-4**, **132a-2**, **132a-3**, and **132a-4** may flow in a direction of returning to the first, second, third, and fourth patch antenna patterns **110a-1**, **110a-2**, **110a-3**, and **110a-4**. Accordingly, a portion of each of radiation patterns of the first, second, third, and fourth patch antenna patterns **110a-1**, **110a-2**, **110a-3**, and **110a-4** relatively adjacent to an adjacent patch antenna pattern may have electromagnetically harmonious properties with respect to a radiation pattern of the adjacent patch antenna pattern.

Thus, as first, second, third, and fourth radiation patterns of the first, second, third, and fourth patch antenna patterns **110a-1**, **110a-2**, **110a-3**, and **110a-4** may be electromagnetically overlap one another in an efficient manner such that an overall gain of the antenna apparatus **100a** may improve.

The antenna apparatus **100a** in the example may further include first, second, third, fourth, fifth, sixth, seventh, and eighth ground vias **123a-1**, **124a-1**, **123a-2**, **123a-3**, **123a-4**, **124a-2**, **124a-3**, and **124a-4** configured to electrically connect the first, second, third, fourth, fifth, sixth, seventh, and eighth coupling patterns **131a-1**, **132a-1**, **131a-2**, **131a-3**, **131a-4**, **132a-2**, **132a-3**, and **132a-4** to the ground plane **201a**.

Referring to FIGS. 1A through 1E, a space overlapping the supplementary patch patterns **136a-1**, **136a-2**, **136a-3**, and **136a-4** in upward and/or downward directions and disposed on a level the same as levels of the first, second, third, fourth, fifth, sixth, seventh, and eighth coupling patterns **131a-1**, **132a-1**, **131a-2**, **131a-3**, **131a-4**, **132a-2**, **132a-3**, and **132a-4** may be formed of a non-conductive material or air.

Accordingly, the dispersion of directions of surface currents of the first, second, third, and fourth patch antenna patterns **110a-1**, **110a-2**, **110a-3**, and **110a-4** may be prevented. Accordingly, the first, second, third, and fourth radiation patterns of the first, second, third, and fourth patch antenna patterns **110a-1**, **110a-2**, **110a-3**, and **110a-4** may electromagnetically overlap each other in an efficient manner such that an overall gain of the antenna apparatus **100a** may improve.

Referring to FIGS. 1A through 1E, the fourth conductive layer **104a** of the antenna apparatus **100a** in the example may include first, second, third, fourth, fifth, sixth, seventh, and eighth feed lines **220a-8**, **220a-5**, **220a-2**, **220a-1**, **220a-7**, **220a-3**, **220a-4**, and **220a-6** electrically connected to the first, second, third, fourth, fifth, sixth, seventh, and eighth feed vias **120a-8**, **120a-5**, **120a-2**, **120a-1**, **120a-7**, **120a-3**, **120a-4**, and **120a-6**, respectively.

As shown in FIGS. 1D and 1F, the antenna apparatus **100a** may further include a plurality of shielding vias **245a** electrically connected to the ground plane **201a**. The plurality of shielding vias **245a** may be arranged to surround the first, second, third, fourth, fifth, sixth, seventh, and eighth feed vias **120a-8**, **120a-5**, **120a-2**, **120a-1**, **120a-7**, **120a-3**, **120a-4**, and **120a-6** in upward and/or downward directions (e.g., +/-z directions), respectively.

FIGS. 2A through 2C are plan diagrams illustrating modified structures of a first conductive layer of an antenna apparatus according to an example.

Referring to FIG. 2A, a supplementary patch pattern **136b** disposed on a first conductive layer **101b** of an antenna apparatus in the example may have a single polygonal shape, which may have a dimension **WP3**.

Referring to FIG. 2B, a first conductive layer **101c** of the antenna apparatus in the example may have a structure in which a supplementary patch pattern is not provided.

Referring to FIG. 2C, a first conductive layer **101d** of the antenna apparatus in the example may have a structure in which an upper coupling pattern is not provided.

FIGS. 3A and 3B are plan diagrams illustrating a modified structure of an antenna apparatus according to an example.

Referring to FIG. 3A, first, second, third, and fourth upper patch patterns **115a-1**, **115a-2**, **115a-3**, **115a-4** of a first conductive layer **101e** of an antenna apparatus may be electrically connected to at least one of first, second, third, fourth, fifth, sixth, seventh, and eighth feed vias **120a-8**, **120a-5**, **120a-2**, **120a-1**, **120a-7**, **120a-3**, **120a-4**, and **120a-6**.

6, and may be fed with power from the first, second, third, fourth, fifth, sixth, seventh, and eighth feed vias **120a-8**, **120a-5**, **120a-2**, **120a-1**, **120a-7**, **120a-3**, **120a-4**, and **120a-6** in a contact manner.

Referring to FIG. 3B, first, second, third, and fourth patch antenna patterns **110a-1**, **110a-2**, **110a-3**, and **110a-4** of a second conductive layer **102e** of an antenna apparatus may have a through-hole through which at least one of the first, second, third, fourth, fifth, sixth, seventh, and eighth feed vias **120a-8**, **120a-5**, **120a-2**, **120a-1**, **120a-7**, **120a-3**, **120a-4**, and **120a-6** penetrates, and may be fed with power from the first, second, third, fourth, fifth, sixth, seventh, and eighth feed vias **120a-8**, **120a-5**, **120a-2**, **120a-1**, **120a-7**, **120a-3**, **120a-4**, and **120a-6** in a non-contact manner.

For example, each of the first, second, third, and fourth upper patch patterns **115a-1**, **115a-2**, **115a-3**, and **115a-4** may have a size smaller than a size of each of the first, second, third, and fourth patch antenna patterns **110a-1**, **110a-2**, **110a-3**, and **110a-4**, and may be configured to have a resonant frequency higher than a resonant frequency of each of the first, second, third, and fourth patch antenna patterns **110a-1**, **110a-2**, **110a-3**, and **110a-4**. Accordingly, the antenna apparatus in the example may be configured to have a plurality of different frequency bands (e.g., 28 GHz and 39 GHz).

FIG. 4A is a plan diagram illustrating a modified structure of a ground plane of an antenna apparatus according to an example.

Referring to FIG. 4A, an antenna apparatus in the example may include a ground plane **201f** through which at least one of first, second, third, fourth, fifth, sixth, seventh, and eighth feed vias **120a-12**, **120a-10**, **120a-11**, **120a-9**, **120a-13**, **120a-14**, **120a-16**, and **120a-15** of a third conductive layer **103f** is configured to penetrate.

The antenna apparatus in the example may further include a plurality of shielding vias **245f** electrically connected to the ground plane **201f**. The plurality of shielding vias **245f** may be arranged to surround the first, second, third, fourth, fifth, sixth, seventh, and eighth feed vias **120a-12**, **120a-10**, **120a-11**, **120a-9**, **120a-13**, **120a-14**, **120a-16**, and **120a-15** in upward and/or downward directions (e.g., +/-z directions), respectively.

FIGS. 4B through 4E are plan diagrams illustrating a structure disposed lower than a ground plane of an antenna apparatus. FIGS. 4F is a cross-sectional diagram illustrating a structure disposed lower than a ground plane of an antenna apparatus.

Referring to FIGS. 4B through 4F, a fourth conductive layer **104f** of an antenna apparatus in the example may further include a second ground plane **202f** configured to surround first, second, third, fourth, fifth, sixth, seventh, and eighth feed lines **220a-12**, **220a-10**, **220a-11**, **220a-9**, **220a-13**, **220a-14**, **220a-16**, and **220a-15**.

The shielding vias **245f** may be electrically connected to the second ground plane **202f**. The plurality of shielding vias **245f** may be arranged to surround the first, second, third, fourth, fifth, sixth, seventh, and eighth feed lines **220a-12**, **220a-10**, **220a-11**, **220a-9**, **220a-13**, **220a-14**, **220a-16**, and **220a-15** in upward and/or downward directions (e.g., +/-z directions), respectively.

Each of the first, second, third, fourth, fifth, sixth, seventh, and eighth feed lines **220a-12**, **220a-10**, **220a-11**, **220a-9**, **220a-13**, **220a-14**, **220a-16**, and **220a-15** may include an impedance transformer **228f**.

Referring to FIGS. 4C, 4D, and 4F, fifth and sixth conductive layers **105f** and **106f** of the antenna apparatus in the example may further include third and fourth ground

planes **203f** and **204f** configured to surround first, second, third, fourth, fifth, sixth, seventh, and eighth wiring vias **230a-12**, **230a-10**, **230a-11**, **230a-9**, **230a-13**, **230a-14**, **230a-16**, and **230a-15**.

5 The first, second, third, fourth, fifth, sixth, seventh, and eighth wiring vias **230a-12**, **230a-10**, **230a-11**, **230a-9**, **230a-13**, **230a-14**, **230a-16**, and **230a-15** may electrically connect the first, second, third, fourth, fifth, sixth, seventh, and eighth feed lines **220a-12**, **220a-10**, **220a-11**, **220a-9**, **220a-13**, **220a-14**, **220a-16**, and **220a-15** to an IC.

10 The shielding vias **245f** may be electrically connected to the third and fourth ground planes **203f** and **204f**, respectively. The plurality of shielding vias **245f** may be arranged to surround the first, second, third, fourth, fifth, sixth, seventh, and eighth wiring vias **230a-12**, **230a-10**, **230a-11**, **230a-9**, **230a-13**, **230a-14**, **230a-16**, and **230a-15** in upward and/or downward directions (e.g., +/-z directions), respectively.

15 Referring to FIGS. 4D, 4E, and 4F, a seventh conductive layer **107f** of the antenna apparatus in the example may further include a plurality of electrical interconnect structures **330f** electrically connected to the first, second, third, fourth, fifth, sixth, seventh, and eighth wiring vias **230a-12**, **230a-10**, **230a-11**, **230a-9**, **230a-13**, **230a-14**, **230a-16**, and **230a-15** (collectively **230a**). The plurality of electrical interconnect structures **330f** may support the mounting of an IC. A fifth ground plane **205f** disposed on the seventh conductive layer **107f** may surround the plurality of electrical interconnect structures **330f**.

20 FIGS. 5A and 5B are side views of a connection member on which a ground plane is stacked, included in an antenna device, and a lower structure of the connection member according to an example embodiment.

25 Referring to FIG. 5A, an antenna apparatus in the example may include at least some of a connection member **200**, an IC **310**, an adhesive member **320**, an electrical interconnect structure **330**, an encapsulant **340**, a passive component **350**, and a sub-substrate **410**.

30 The connection member **200** may have a structure in which the plurality of ground planes described in the aforementioned example examples may be stacked.

35 The IC **310** may be the same as the IC described in the aforementioned examples, and may be disposed below the connection member **200**. The IC **310** may be connected to a wiring line of the connection member **200** and may transmit an RF signal to and receive an RF signal from the connection member **200**. The IC **310** may also be electrically connected to a ground plane and may be provided with a ground. For example, the IC **310** may perform at least some of operations of frequency conversion, amplification, filtering, phase control, and power generation and may generate a converted signal.

40 The adhesive member **320** may attach the IC **310** to the connection member **200**.

45 The electrical interconnect structure **330** may electrically connect the IC **310** to the connection member **200**. For example, the electrical interconnect structure **330** may have a structure such as that of a solder ball, a pin, a land, and a pad. The electrical interconnect structure **330** may have a melting point lower than that of a wiring line and a ground plane of the connection member **200** such that the electrical interconnect structure **330** may electrically connect the IC **310** to the connection member **200** through a required process using the low melting point.

50 The encapsulant **340** may encapsulate at least a portion of the IC **310**, and may improve heat dissipation performance and protection performance against impacts. For example,

the encapsulant 340 may be implemented by a photoimageable encapsulant (PIE), an Ajinomoto build-up film (ABF), an epoxy molding compound (EMC), or the like.

The passive component 350 may be disposed on a lower surface of the connection member 200, and may be electrically connected to a wiring line and/or a ground plane of the connection member 200 through the electrical interconnect structure 330.

The sub-substrate 410 may be disposed below the connection member 200, and may be electrically connected to the connection member 200 to receive an intermediate frequency (IF) signal or a baseband signal from an external entity and to transmit the signal to the IC 310, or to receive an IF signal or a baseband signal from the IC 310 and to transmit the signal to an external entity. A frequency of an RF signal (e.g., 24 GHz, 28 GHz, 36 GHz, 39 GHz, 60 GHz) may be higher than a frequency of an IF signal (e.g., 2 GHz, 5 GHz, 10 GHz, or the like).

For example, the sub-substrate 410 may transmit an IF signal or baseband signal to the IC 310 or may receive an IF signal or baseband signal from the IC 310 through a wiring line included in an IC ground plane. As a first ground plane of the connection member 200 is disposed between the IC ground plane and a wiring line, an IF signal or a baseband signal and an RF signal may be electrically isolated from each other in an antenna module.

Referring to FIG. 5B, the antenna apparatus in the example may include at least some of a shielding member 360, a connector 420, and a chip antenna 430.

The shielding member 360 may be disposed below the connection member 200 and may enclose the IC 310 along with the connection member 200. For example, the shielding member 360 may cover or conformally shield the IC 310 and the passive component 350 together, or may separately cover or compartment-shield the IC 310 and the passive component 350. For example, the shielding member 360 may have a hexahedral shape in which one surface is open, and may have an accommodation space having a hexahedral form by being combined with the connection member 200. The shielding member 360 may be implemented by a material having relatively high conductivity such as copper such that the shielding member 360 may have a relatively short skin depth, and the shielding member 360 may be electrically connected to a ground plane of the connection member 200. Accordingly, the shielding member 360 may reduce electromagnetic noise which the IC 310 and the passive component 350 may receive.

The connector 420 may have a connection structure of a cable (e.g., a coaxial cable or a flexible PCB), may be electrically connected to the IC ground plane of the connection member 200, and may work similarly to the above-described sub-substrate. Accordingly, the connector 420 may be provided with an IF signal, a baseband signal, and/or power from a cable, or may provide an IF signal and/or a baseband signal to a cable.

The chip antenna 430 may transmit and/or receive an RF signal in addition to the antenna apparatus. For example, the chip antenna 430 may include a dielectric block having a dielectric constant higher than that of an insulating layer, and a plurality of electrodes disposed on both surfaces of the dielectric block. One of the plurality of electrodes may be electrically connected to a wiring line of the connection member 200, and the other one of the plurality of electrodes may be electrically connected to a ground plane of the connection member 200.

FIGS. 6A and 6B are plan diagrams illustrating an arrangement of an antenna apparatus in an electronic device according to an example.

Referring to FIG. 6A, an antenna apparatus 100g including a patch antenna pattern 1110g and a dielectric layer 1140g may be disposed adjacent to a side surface boundary of an electronic device 700g on a set substrate 600g of the electronic device 700g.

The electronic device 700g may be implemented by a smartphone, a personal digital assistant, a digital video camera, a digital still camera, a network system, a computer, a monitor, a tablet PC, a laptop PC, a netbook PC, a television, a video game, a smart watch, an automotive component, or the like, but an example of the electronic device 700g is not limited thereto.

A communication module 610g and a baseband circuit 620g may further be disposed on the set substrate 600g. The antenna module may be electrically connected to the communication module 610g and/or the baseband circuit 620g through a coaxial cable 630g.

The communication module 610g may include at least some of a memory chip such as a volatile memory (e.g., a DRAM), a non-volatile memory (e.g., a ROM), a flash memory, or the like; an application processor chip such as a central processor (e.g., a CPU), a graphics processor (e.g., a GPU), a digital signal processor, a cryptographic processor, a microprocessor, a microcontroller, or the like; and a logic chip such as an analog-to-digital converter, an application-specific integrated circuit (ASIC), or the like.

The baseband circuit 620g may generate a base signal by performing analog-to-digital conversion, and amplification, filtering, and frequency conversion on an analog signal. A base signal input to and output from the baseband circuit 620g may be transferred to the antenna module through a cable.

For example, the base signal may be transferred to an IC through an electrical interconnect structure, a cover via, and a wiring line. The IC may convert the base signal into an RF signal of millimeter wave (mmWave) band.

Referring to FIG. 6B, a plurality of antenna apparatuses 100i each including a patch antenna pattern 1110i may be disposed adjacent to a center of an edge of a polygonal electronic device 700i on a set substrate 600i of the electronic device 700i, and a communication module 610i and a baseband circuit 620i may further be disposed on the set substrate 600i. The plurality antenna apparatuses and the antenna modules may be electrically connected to the communication module 610i and/or baseband circuit 620i through a coaxial cable 630i.

The pattern, the via, the line, and the plane described in the aforementioned example embodiments may include a metal material (e.g., a conductive material such as copper (Cu), aluminum (Al), silver (Ag), tin (Sn), gold (Au), nickel (Ni), lead (Pb), titanium (Ti), or alloys thereof), and may be formed by a plating method such as a chemical vapor deposition (CVD) method, a physical vapor deposition (PVD) method, a sputtering method, a subtractive method, an additive method, a semi-additive process (SAP), a modified semi-additive process (MSAP), or the like, but examples of the material and the method are not limited thereto.

The dielectric layer in the example embodiments may be implemented by a material such as FR4, a liquid crystal polymer (LCP), low temperature co-fired ceramic (LTCC), a thermosetting resin such as an epoxy resin, a thermoplastic resin such as a polyimide resin, a resin in which the above-described resin is impregnated in a core material,

such as a glass fiber (or a glass cloth or a glass fabric), together with an inorganic filler, such as prepreg, a Ajinomoto build-up film (ABF), FR-4, bismaleimide triazine (BT), a photoimangible dielectric (PID) resin, a general copper clad laminate (CCL), glass or a ceramic-based insulating material, or the like.

The RF signal described in the example embodiments may include protocols such as wireless fidelity (Wi-Fi) (Institute of Electrical And Electronics Engineers (IEEE) 802.11 family, or the like), worldwide interoperability for microwave access (WiMAX) (IEEE 802.16 family, or the like), IEEE 802.20, long term evolution (LTE), evolution data only (Ev-DO), high speed packet access +(HSPA+), high speed downlink packet access +(HSDPA+), high speed uplink packet access +(HSUPA+), enhanced data GSM environment (EDGE), global system for mobile communications (GSM), global positioning system (GPS), general packet radio service (GPRS), code division multiple access (CDMA), time division multiple access (TDMA), digital enhanced cordless telecommunications (DECT), Bluetooth, 3G, 4G, and 5G protocols, and any other wireless and wired protocols designated after the above-mentioned protocols, but an example is not limited thereto.

According to the aforementioned examples, the antenna apparatus may have improved antenna performances (e.g., a gain, a bandwidth, directivity, and the like), and/or may be easily miniaturized.

While this disclosure includes specific examples, it will be apparent to one of ordinary skill in the art that various changes in form and details may be made in these examples without departing from the spirit and scope of the claims and their equivalents. The examples described herein are to be considered in a descriptive sense only, and not for purposes of limitation. Descriptions of features or aspects in each example are to be considered as being applicable to similar features or aspects in other examples. Suitable results may be achieved if the described techniques are performed to have a different order, and/or if components in a described system, architecture, device, or circuit are combined in a different manner, and/or replaced or supplemented by other components or their equivalents. Therefore, the scope of the disclosure is defined not by the detailed description, but by the claims and their equivalents, and all variations within the scope of the claims and their equivalents are to be construed as being included in the disclosure.

What is claimed is:

1. An antenna apparatus, comprising:
  - a ground plane;
  - a first patch antenna pattern disposed above and spaced apart from a first surface of the ground plane;
  - a second patch antenna pattern disposed above and spaced apart from the first surface of the ground plane, and spaced apart from the first patch antenna pattern;
  - a first feed via configured to provide a first feed path of the first patch antenna pattern through a first point of the first patch antenna pattern, and disposed adjacent to an edge of the first patch antenna pattern in a direction in which the first point is spaced apart from the second patch antenna pattern;
  - a second feed via configured to provide a second feed path of the second patch antenna pattern through a second point of the second patch antenna pattern, and disposed adjacent to an edge of the second patch antenna pattern in a direction in which the second point is spaced apart from the first patch antenna pattern; and
  - a first coupling pattern disposed between the first patch antenna pattern and the second patch antenna pattern,

and spaced apart from the first patch antenna pattern and the second patch antenna pattern, and configured to define a first internal space of the first coupling pattern that is exposed towards the first patch antenna pattern.

2. The antenna apparatus of claim 1, further comprising: a second coupling pattern disposed between the second patch antenna pattern and the first coupling pattern, and spaced apart from the first coupling pattern, and configured to define a second internal space of the second coupling pattern that is exposed towards the second patch antenna pattern.
3. The antenna apparatus of claim 2, further comprising: a first ground via electrically connecting the first coupling pattern to the ground plane; and a second ground via electrically connecting the second coupling pattern to the ground plane.
4. The antenna apparatus of claim 3, wherein the first ground via is electrically connected to a point of the first coupling pattern adjacent to the second coupling pattern, and wherein the second ground via is electrically connected to a point of the second coupling pattern adjacent to the first coupling pattern.
5. The antenna apparatus of claim 2, wherein a gap between the first coupling pattern and the second coupling pattern is smaller than a gap between the first coupling pattern and the first patch antenna pattern.
6. The antenna apparatus of claim 5, wherein a length of the first coupling pattern along a direction perpendicular to a direction in which the first and second coupling patterns oppose each other is larger than a width of the first coupling pattern.
7. The antenna apparatus of claim 2, further comprising: an upper coupling pattern disposed above and spaced apart from the first coupling pattern and the second coupling pattern such that the first coupling pattern and the second coupling pattern are disposed between the ground plane and the upper coupling pattern along a direction perpendicular to the first surface of the ground plane, and configured to overlap the first coupling pattern and the second coupling pattern in the direction perpendicular to the first surface of the ground plane.
8. The antenna apparatus of claim 7, wherein the upper coupling pattern is configured to overlap a gap between the first coupling pattern and the second coupling pattern, the first internal space of the first coupling pattern, and the second internal space of the second coupling pattern in a direction perpendicular to the first surface of the ground plane.
9. The antenna apparatus of claim 7, further comprising: a first upper patch pattern disposed above and spaced apart from the first patch antenna pattern; a second upper patch pattern disposed above and spaced apart from the second patch antenna pattern; and a supplementary patch pattern spaced apart from the upper coupling pattern along a direction different from at least one direction in which the supplementary patch pattern spaced is apart from the first upper patch pattern and the second upper patch pattern.
10. The antenna apparatus of claim 9, wherein the supplementary patch pattern includes a plurality of supplementary patch patterns spaced apart from each other, and each having a size smaller than a size of the upper coupling pattern.
11. The antenna apparatus of claim 1, further comprising: a first upper patch pattern disposed above and spaced apart from the first patch antenna pattern;

21

a second upper patch pattern disposed above and spaced apart from the second patch antenna pattern; and an upper coupling pattern disposed above and spaced apart from the first coupling pattern, and configured to overlap the first coupling pattern in a direction perpendicular to the first surface of the ground plane. 5

12. The antenna apparatus of claim 2, further comprising: a third patch antenna pattern disposed above and spaced apart from the first surface of the ground plane, and spaced apart from the first patch antenna pattern and the second patch antenna pattern; 10 a fourth patch antenna pattern disposed above and spaced apart from the first surface of the ground plane and spaced apart from the first patch antenna pattern, the second patch antenna pattern, and the third patch antenna pattern; 15 a fourth coupling pattern disposed between the first patch antenna pattern and the third patch antenna pattern, and spaced apart from the first patch antenna pattern and the third patch antenna pattern, and configured to define a third internal space of the fourth coupling pattern that is exposed towards the first patch antenna pattern; and a fourth coupling pattern disposed between the second patch antenna pattern and the fourth patch antenna pattern, and spaced apart from the second patch antenna pattern and the fourth patch antenna pattern, and configured to define a fourth internal of the fourth coupling pattern space that is exposed towards the second patch antenna pattern. 20 25

13. The antenna apparatus of claim 12, further comprising: 30

a fifth coupling pattern disposed between the third patch antenna pattern and the fourth patch antenna pattern, and configured to define a fifth internal space of the fifth coupling pattern that is exposed towards the third patch antenna pattern; 35

a sixth coupling pattern spaced disposed between the third patch antenna pattern and the third coupling pattern, and spaced apart from the third coupling pattern, and configured to define a sixth internal space of the sixth coupling pattern that is exposed towards the third patch antenna pattern; 40

a seventh coupling pattern disposed between the fourth patch antenna pattern and the fourth coupling pattern, and spaced apart from the fourth coupling pattern, and configured to define a seventh internal space of the seventh coupling pattern that is exposed towards the fourth patch antenna pattern; and 45

an eighth coupling pattern disposed between the fourth patch antenna pattern and the fifth coupling pattern, and spaced apart from the fifth coupling pattern, and configured to define an eighth internal space of the eighth coupling pattern that is exposed towards the fourth patch antenna pattern. 50

14. The antenna apparatus of claim 12, further comprising: 55

a third feed via configured to provide a third feed path of the first patch antenna pattern through a third point of the first patch antenna pattern, and disposed adjacent to an edge of the first patch antenna pattern in a direction in which the third point is spaced apart from the third patch antenna pattern; 60

a fourth feed via configured to provide a fourth feed path of the second patch antenna pattern through a fourth point of the second patch antenna pattern, and disposed adjacent to an edge of the second patch antenna pattern 65

22

in a direction in which the fourth point is spaced apart from the fourth patch antenna pattern;

a fifth feed via configured to provide a fifth feed path of the third patch antenna pattern through a fifth point of the third patch antenna pattern, and disposed adjacent to an edge of the third patch antenna pattern in a direction in which the fifth point is spaced apart from the fourth patch antenna pattern;

a sixth feed via configured to provide a sixth feed path of the third patch antenna pattern through a sixth point of the third patch antenna pattern, and disposed adjacent to an edge of the third patch antenna pattern in a direction in which the sixth point is spaced apart from the first patch antenna pattern;

a seventh feed via configured to provide a seventh feed path of the fourth patch antenna pattern through a seventh point of the fourth patch antenna pattern, and disposed adjacent to an edge of the fourth patch antenna pattern in a direction in which the seventh point is spaced apart from the second patch antenna pattern; and

an eighth feed via configured to provide an eighth feed path of the fourth patch antenna pattern through an eighth point of the fourth patch antenna pattern, and disposed adjacent to an edge of the fourth patch antenna pattern in a direction in which the eighth point is spaced apart from the third patch antenna pattern.

15. The antenna apparatus of claim 12, further comprising:

a fifth coupling pattern disposed between the third patch antenna pattern and fourth patch antenna patterns, and configured to define a fifth internal space exposed towards the third patch antenna pattern; and

a plurality of upper coupling patterns disposed above and spaced apart from the first coupling pattern, the second coupling pattern, the third coupling pattern, the fourth coupling pattern, and the fifth coupling pattern such that the first coupling pattern, the second coupling pattern, the third coupling pattern, the fourth coupling pattern, and the fifth coupling pattern are disposed between the ground plane and the upper coupling patterns along a direction perpendicular to the first surface of the ground plane, and configured to overlap the first coupling pattern, the second coupling pattern, the third coupling pattern, the fourth coupling pattern, and the fifth coupling pattern in the direction perpendicular to the first surface of the ground plane.

16. The antenna apparatus of claim 15, further comprising:

a plurality of supplementary patch patterns surrounded by the upper coupling patterns, spaced apart from each other, and each having a size smaller than a size of each of the upper coupling patterns.

17. The antenna apparatus of claim 15, further comprising:

a supplementary patch pattern surrounded by the upper coupling patterns, wherein a space overlapping the supplementary patch pattern in the direction perpendicular to the first surface of the ground plane and disposed on a same level as the first coupling pattern, the second coupling pattern, the third coupling pattern, the fourth coupling pattern, and the fifth coupling pattern is formed of a non-conductive material or air.
